CLAIM

The ornamental design for a ridge vent metal cap, as shown and described.

DESCRIPTION

FIG. 1 is a top, front-left, perspective view of a ridge vent metal cap, showing our new design;

FIG. 2 is a top, front-right, perspective view thereof;

FIG. 3 is a left-side elevation view thereof;

FIG. 4 is a right-side elevation view thereof;

FIG. 5 is a rear elevation view thereof;

FIG. 6 is a front elevation view thereof;

FIG. 7 is a top view thereof; and,

FIG. 8 is a bottom view thereof.

The broken lines shown on the drawings are for illustrative purposes only and form no part of the claimed design.
